CARTRIDGE DISPENSER

Early P. Fraley, Doraville, Ga.

Application April 14, 1950, Serial No. 156,005

3 Claims. (Cl. 224—18)

1

This invention relates to dispensing containers, and more particularly to a dispensing container for cartridges adapted to be arranged for handling cartridges of different lengths.

A main object of the invention is to provide a novel and improved cartridge dispenser which is simple in construction, which is easy to operate, and which may be readily arranged for handling cartridges of different lengths, for example, short 22-caliber cartridges, long 22-caliber cartridges, and long rifle cartridges.

A further object of the invention is to provide an improved cartridge dispenser which is adjustable for handling cartridges of different lengths, said dispenser being inexpensive to manufacture, involving only a few parts, being sturdy in construction, being neat in appearance, being compact in size and light in weight.

Further objects and advantages of the invention will become apparent from the following description and claims, and from the accompanying drawings, wherein:

Figure 1 is a side elevational view of an improved cartridge dispenser constructed in accordance with the present invention;

Figure 2 is a vertical longitudinal cross-sectional view taken on line 2—2 of Figure 1;

Figure 3 is a horizontal cross-sectional view taken on line 3—3 of Figure 1;

Figure 4 is a horizontal cross-sectional view taken on line 4—4 of Figure 1;

Figure 5 is an expanded perspective view of the lower portion of the main body of the cartridge dispenser and the disc elements and end plate associated therewith.

Referring to the drawings, the cartridge dispenser is designated generally at 11, and comprises an elongated body 12 formed with the longitudinal bores 13 arranged at equal distances from each other around the periphery of the body 12 and located at equal radial distances from the axis of the body. The body is formed with external flutes 14 which are substantially concentric with the bores 13, as shown in Figure 5. The flutes are evenly spaced around the periphery of the body, and one of the flutes, designated at 14' is not formed with a longitudinal bore, defining a solid or blank space 15. Rotatably secured to one end of the body 12 is a cover disc 16 formed with an aperture 17 located at the same radial distance as the bores 13 and adapted to be registered therewith for inserting cartridges into said bores. The cover disc 16 is secured at its center to the center of the end of the body 12 by a screw 18 and is formed on its inner surface with circu-

2

larly arranged spaced recesses 19 lockingly engageable by a spring pressed ball 20 carried by the body 12 for releasably locking the end disc 16 in respective positions wherein the aperture 17 registers with respective bores 13, whereby cartridges may be inserted in said bores. The ends of the bores are closed when the aperture 17 is positioned adjacent the blank space 15 of the flute 14'.

Projecting axially from the opposite end of the body 12 is a stud 21, and rotatably mounted on said stud are the respective disc elements 22, 23 and 24. Designated at 25 is an end plate fastened at its center to the end of the stud 21 by a machine screw 26 and locked against rotation with respect to said stud by an offset projection 27 carried by the end of the stud 21 and engaged in an opening 28 in the end plate 25. The end plate 25 is formed with an aperture 29 which is at the same radial distance from the axis of the body 12 as the bore 13, but is in longitudinal alignment with the blank space 15 of the solid flute 14'. The respective disc elements 22, 23 and 24 are formed with respective peripherally arranged apertures, shown respectively at 30, 31 and 32, located at the same radial distances as the bores 13 from the axis of the stud 21 and being equal in number to the combined total of the flutes 14 and 14' of the body 12.

As shown in Figure 2, the disc element 22 is formed with a central thickened portion 33. Opposite said thickened portion 33 the disc element 22 is formed with a projection 34 which is received in a recess 35 formed in the adjacent disc element 23. The body 12 is formed opposite the recess 35 with a recess 36 adapted to receive the projection 34 when the disc element 22 is reversed.

The disc element 23 is formed with a projection 37 longitudinally aligned with its recess 35, said projection 37 being received in a recess 38 formed in the disc element 24. The disc element 24 is releasably locked to the plate 25 by a spring pressed ball 39 carried in the disc element 24 which is receivable in spaced recesses 40 formed in the plate 25 for locking a selected aperture 32 of the plate 24 in registry with the opening 29 of the plate 25.

Secured to the body 12 is a spring clip 41 for engaging over the belt of the user, whereby the cartridge dispenser may be conveniently carried.

With the dispenser arranged as shown in Figures 1 and 2, it will be seen that the disc elements 22, 23 and 24 are locked together for rotation as a unit around the stud 21. This provides a relatively long combined length of the register-

ing apertures 30, 31 and 32 of the disc elements. With this arrangement, the dispenser may be employed to handle long rifle cartridges, inasmuch as the combined length of the apertures 30, 31 and 32 corresponds to the length of such long rifle cartridges, and the cartridges may be fed to said relatively long combined apertures from the bores 13 of the body 12. By rotating the locked disc elements 22, 23 and 24 around the stud 21, the cartridges carried in the disc elements 22, 23 and 24 may be successively dispensed through the opening 29 in the plate 25. When it is desired to dispense cartridges of the next shorter lengths, for example, long 22-caliber cartridges, the disc elements 23, 22 and 24 are 15 disassembled from the stud 21 by removing the end plate 25 and the disc elements are replaced with the disc element 22 in reversed position, whereby its lug 34 enters the opening 36 of the body 12 and is effective to lock the disc element 22 to the body. Under these conditions, only the disc elements 23 and 24 are rotatable on the stud 21, and the combined lengths of the openings 31 and 32 correspond to the lengths of a 22-caliber long cartridge. When it is desired to employ the device for dispensing 22-caliber short cartridges, the disc elements 22, 23 and 24 are 20 disassembled from the stud 21 and are reassembled with the disc element 23 located adjacent to the end of the body 12 with the lug 37 of said disc element received in the recess 36 of the body 12. The disc element 22 is positioned adjacent the disc element 23 with its projection 34 received in the recess 35 of the disc element 23 and with its thickened portion 33 projecting 25 downwardly. The disc element 24 is rotatably mounted on the stud 21 adjacent the disc element 22 in its usual manner. With this arrangement, the disc elements 23 and 22 are locked against rotation with respect to the body 12, and only the disc element 24 may rotate. Since the length of the aperture 32 of the disc element 24 corresponds to the length of 22-caliber short cartridges, it will be seen that the short cartridges may be dispensed from the device by 30 rotating the disc element 24 to bring the apertures 32 into successive registry with the opening 29 of the end plate 25.

While a specific embodiment of an adjustable cartridge dispenser has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A cartridge dispenser for dispensing cartridges of various lengths comprising an elongated body formed with longitudinal bores uniformly spaced at equal distances from each other and located at equal radial distances from the axis of the body, a cover plate rotatably secured to one end of the body, said plate being formed with an opening selectively registerable 65 with said bores, an axial stud projecting from the other end of the body, a plurality of disc elements of varying thickness rotatably mounted on said stud, said disc elements being formed with apertures registerable with the bores, an end plate 70 detachably secured on the stud, said end

plate being formed with an opening arranged to register selectively with the apertures of the disc elements, and means for at times locking certain of said disc elements against rotation relative to said body.

2. A cartridge dispenser for dispensing cartridges of various lengths comprising an elongated body formed with longitudinal bores uniformly spaced at equal distances from each other and located at equal radial distances from the axis of the body, a cover plate rotatably secured to one end of the body, said plate being formed with an opening selectively registerable with said bores, an axial stud projecting from the other end of the body, a plurality of disc elements of varying thickness rotatably mounted on said stud, said disc elements being formed with apertures registerable with the bores, an end plate detachably secured on the stud, said end plate being formed with an opening arranged to register selectively with the apertures of the disc elements, a recess formed in the end of the body facing the disc elements, recesses formed in the respective disc elements, and projections on said disc elements arranged to be received in said recesses, whereby certain of said disc elements may at times be locked against rotation with respect to the body and at other times the disc elements may be locked for simultaneous rotation around said stud.

3. A cartridge dispenser for dispensing cartridges of various lengths comprising an elongated body formed with longitudinal bores uniformly spaced at equal distances from each other and located at equal radial distances from the axis of the body, a cover plate rotatably secured to one end of the body, said plate being formed with an opening selectively registerable with said bores, an axial stud projecting from the other end of the body, a plurality of disc elements of varying thickness rotatably mounted on said stud, said disc elements being formed with apertures registerable with the bores, an end plate detachably secured on the stud, said end plate being formed with an opening arranged to register selectively with the apertures of the disc elements, a recess formed in the end of the body facing the disc elements, recesses formed in the respective disc elements, projections on said disc elements arranged to be received in said recesses, whereby certain of said disc elements may at times be locked against rotation with respect to the body and at other times the disc elements may be locked for simultaneous rotation around said stud, and interengaging resilient detent means provided between the end disc element and the end plate yieldably locking the end disc element in positions wherein the aperture in the end plate registers with the apertures in the end disc element.
